(57) **CLAIM**

The ornamental design for a medical instrument for eye surgical purposes, as shown and described.

DESCRIPTION

FIG. 1 is a perspective view of the medical instrument for eye surgical purposes showing our new design;

FIG. 2 is a front elevation view thereof;

FIG. 3 is a back side view thereof;

FIG. 4 is a right side view thereof;

FIG. 5 is a left side view thereof;

FIG. 6 is a top view thereof; and,

FIG. 7 is a bottom view thereof.

The broken lines shown in FIGS. 1-7 illustrate portions of the medical instrument for eye surgical purposes that form no part of the claimed design.

1 Claim, 7 Drawing Sheets
